UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

COMPRESSING-MACHINE.

1,172,471.

Specification of Letters Patent. Patented Feb. 22, 1916.

Application filed May 12, 1910. Serial No. 560,874.

To all whom it may concern:

Be it known that I, THOMAS LUND, a citizen of the United States, residing at Beverly, in the county of Essex and State of Massachusetts, have invented certain Improvements in Compressing-Machines, of which the following description, in connection with the accompanying drawings, is a specification, like reference characters on 10 the drawings indicating like parts in the several figures.

This invention relates to machines for compressing leather blanks, such as heels or top lifts. In one well known type of machine used in this class of work a stationary die or follower is employed and a mold is arranged for reciprocation toward and from said die. The mold is so constructed as to contract during its movement toward the die 20 or follower to compress laterally a blank previously placed therein. The bottom of the mold is formed by a top lift plate, so called, and mechanism is provided for elevating the top lift plate relatively to the remainder of the mold, during the movement of the mold away from the stationary die, to eject a compressed heel or top lift from the mold. Feeding mechanism is also provided for removing a compressed heel or 25 top lift and supplying an uncompressed blank to the mold. In machines of this kind it is important that the parts be so operated as to allow sufficient time for the handling of the blank with certainty and 30 accuracy.

One important object of the present invention is to provide novel and improved mechanism for operating the top lift plate in proper timed relation to the operation of 35 the other parts of the mold.

With this object in view, a prominent feature of the invention consists in the provision, in a compressing machine having a contractile mold, of frictionally operated 40 means for ejecting a compressed blank from the mold. I have thus succeeded in producing a machine in which the most advan-

tageous timing of the operation of the parts may be secured, while the mechanism is more simple, cheaper to construct, and more 50 certain and accurate in operation than is the case with the machines heretofore known in the art.

In the illustrated embodiment of the invention, the desired results are accomplished 55 simply and effectively by maintaining a lever with a shiftable fulcrum in operative relation to the top lift plate and connecting said lever with the movable mold carrying head of the machine in such a manner as to 60 cause actuation of the lever at the desired points in the movement of the head, the shifting movement of the fulcrum being against friction or resistance which permits 65 lost movement to occur after, or before and after, the movement of the top lift plate. By this means the top lift plate may be actuated to eject a compressed heel or top lift as soon as the mold has expanded enough to release the compressed blank, allowing the 70 longest possible time for removing the compressed blank and supplying an uncompressed blank to the mold. Furthermore, I am able to lower the top lift plate promptly 75 when the mold begins to approach the stationary die, to the end that the blank may be safely deposited at the bottom of the mold before the mold has contracted by any substantial amount.

It is desirable to provide mechanism for 80 insuring a positive action of the ejector in case a blank should stick in the mold and such mechanism constitutes an important feature of the present invention.

In a preferred embodiment of the invention 85 the fulcrum of the ejector actuating lever is carried by a frictionally held rod, and in this embodiment of the invention a positive action of the lever may be secured by providing a locking device arranged to 90 engage said rod and so hold the fulcrum of the lever rigidly, the lever thereupon swinging under the positive actuation of the reciprocating head of the machine. In this

connection the invention contemplates also the provision of mechanism for disengaging the locking device and permitting the normal frictional yielding of the fulcrum-carrying rod, and means for returning the rod to position after it has been displaced.

In the machine above referred to, the automatic mechanism for feeding a blank to the mold and for carrying a compressed heel off the toplift plate, comprises a reciprocating slide carrying a pair of pivoted blank-engaging arms and a two-path switch cam for operating said arms through suitable levers and cam plates.

It is a further object of the present invention to improve and simplify the feeding mechanism in compressing machines and to provide mechanism which shall operate uniformly upon the blank-engaging arms regardless of their position and the direction in which the machine is being operated. This feature is of particular importance in a compressing machine of the type in question since, if the arms are not separated when the head is raised, they will be caught between the mold and the stationary die and damaged.

In a preferred embodiment of my invention a single stationary cam plate may be provided which is so shaped and located relative to the path of devices controlling the blank engaging arms that the required operation is positively secured not only during the normal operation of the machine, but also in case the machine should be turned backwardly from any point of its cycle.

A further important feature of my invention consists in the provision of means for supporting the toplift plate in such a manner that it can be adjusted vertically with relation to the cross head without the necessity of removing the toplift plate and inserting filling pieces, as has been done heretofore. These filling pieces have heretofore been supplied separately or loosely and sufficient of them inserted beneath the toplift plate to raise the same to the elevation required to form the mold of the proper depth to compress the heel or toplift of the particular thickness desired. Such filling pieces as are not in use at any time in the machine are likely to become lost and it is found in use that they frequently become deformed and enlarged in area sufficiently to interfere with the operation of the mold. In the present embodiment of my invention, I dispense entirely with these filling pieces and support the toplift plate directly upon the upper horizontal surface of a wedge shaped block, the lower inclined surface of which engages the upper surface of a correspondingly wedge shaped block which is laterally adjustable with relation to the cross head, on which it rests, so that by adjusting the lower

wedge laterally the upper block may be moved up and down, thus securing the desired vertical adjustment of the toplift plate. On account of the exceedingly great pressure employed in machines of this character, usually amounting to about eighteen tons, or more, it may be, in some cases, undesirable to use smooth wedges to effect the adjustment just referred to since it is difficult to prevent slipping thereof under such great pressure.

A further feature of my invention accordingly consists in the formation of the engaging surfaces of the two wedges in corresponding steps so that at any desired adjustment thereof pressure may be applied to the toplift plate supported upon the upper wedge block without any danger of the latter slipping or yielding.

Other advantages and features of my invention will be best understood and appreciated from the following description of a preferred embodiment thereof selected for purposes of illustration and shown in the accompanying drawings, in which,

Figure 1 is a side elevation of the machine; Fig. 2 is a fragmentary front elevation of the machine; Fig. 3 is a sectional view showing the toplift plate and mechanism for ejecting compressed blanks; Fig. 4 is a view in perspective of the toplift plate mechanism; Fig. 5 is a view in perspective of the feeding device; Fig. 6 is a perspective view of the face of the stationary cam plate which actuates the blank engaging arms; Fig. 7 is a view in perspective of a modified form of toplift plate supporting device mounted in the reciprocating cross head; Fig. 8 is a transverse central section showing the devices illustrated in Fig. 7 with the heel mold in operative relation thereto; and Fig. 9 is a sectional detail upon an enlarged scale showing the formation of the engaging surfaces of the wedge blocks.

1 indicates the rigid frame work of the machine in which the actuating mechanism is supported. Vertical guideways are formed in the sides of the rigid frame and the head 2 is mounted therein for reciprocation. A driving shaft 3 is mounted in bearings in the rear portion of the frame and provided with suitable fast and loose pulleys. The driving shaft carries a pinion 4 which engages with a gear 5 on a counter shaft 6. The counter shaft 6 carries a pinion 7 which meshes with a gear 8 on a crank shaft 9. A link 10 is connected to the crank shaft 9 and also to a toggle composed of members 11 and 12. The toggle member 11 is pivoted at 13 to a rigid portion of the frame near its base. The other toggle 12 is pivoted at 14 to the reciprocating head 2. 15 indicates a chute attached to the frame of the machine and arranged to conduct

away the compressed blanks as they are ejected from the compressing mechanism.

The reciprocating head carries a heel mold comprising a toplift plate 40, a breast-
5 plate 21 and laterally movable side com-
pressing dies 22, one of which is shown in
Fig. 3.

In the upper part of the machine frame
10 and in line with the reciprocating head 2
is formed a rigid abutment 23 upon which
is detachably mounted a heel seat die 25 in
position to co-operate with the mold carried
by the head 2. The side compressing dies
15 22 resting on the top of the head 2 are re-
movably retained in slides 26 in order that
other dies of different shapes may be sub-
stituted in changing from one style of heel
to another.

The side compressing dies and breast
20 plate 21 are actuated to close the mold and
thereafter are opened to release the com-
pressed heel by any desired mechanism, for
instance by normally inclined links 17 piv-
oted on opposite sides to the frame of the
25 machine at 18 as shown in Fig. 2.

The toplift plate 40 is provided with a
downwardly extending stem 41 which is
formed integral therewith, as shown, or may
be otherwise rigidly connected thereto. The
30 stem 41 is slotted at 50 to receive the inner
end of a yieldingly mounted stop pin 51
which acts positively to limit the upward
movement of the toplift plate exactly to
the plane of the table for the feeding mech-
35 anism to be hereinafter described. The stop
pin 51 prevents the plate 40 from being ac-
cidentally expelled from its socket and also
prevents rotary movement thereof, but it
may be withdrawn from engagement with
40 the stem 41 to permit the removal of the
toplift plate when desired. In its lowest
position the toplift plate rests upon the top
of the head 2 although when relatively low
heels are to be compressed one or more shims
45 or filling plates may be placed between the
head and the under side of the toplift plate.

In order to move the toplift plate to eject
a compressed heel at the proper time there is
provided a lever 100 pivotally mounted on
50 the pin 114 in the head 2 of the machine
and having its inner end arranged in align-
ment with the stem 41 of the toplift plate.
Pivotaly connected with the lever 100 by
the pin 112 is a forked piece 101 to the
55 lower end of which is rigidly connected
a rod 102. The rod 102 extends through
a friction box 103 formed in part of the
stationary frame and having a fiber bushing
109 surrounding the rod 102 but cut away
60 on one side to permit a friction plunger 104
to engage the rod and press it against the
bushing thus frictionally opposing vertical
movement of the rod in both directions. It
will be seen that, in the downward move-

ment of the head 2, the pivot pin 112 mo-
mentarily acts as a fulcrum for the lever
100 and causes it to swing upwardly about
the point into contact with the stem 41
which it elevates, thus moving the toplift
plate 40 into position to eject a compressed
heel and receive a heel to be compressed.

Normally the frictional resistance of the
rod 102 will be sufficient to hold the fulcrum
pin 112 of the lever 100 stationary and thus
swing the lever upwardly to elevate the top-
lift plate, but in order to secure a positive
action of the lever 100 at the proper point
in the cycle of the machine, in case a heel
should stick in the mold, a yoke-shaped
piece 105 provided with an abutment 106
is pivoted on a pin 107 to the frame of the
machine and normally maintained by a
spring 108 in position to engage the lower
end of the forked member 101 in case the
lever 100 should be forced downwardly
against the friction of the rod 102 without
lifting the toplift plate. The abutment 106
will, in this event, hold the forked member
101 stationary and insure an immediate posi-
tive movement of the lever on the downward
movement of the head 2 until the toplift
plate has been moved to its ejecting position.
In order to move the member 105 into an in-
operative position and release the forked
member 101 and allow further downward
movement of the rod 102 when the toplift
plate has reached its ejecting position, a
wedge cam 110 is mounted upon the head 2
and arranged to engage with the beveled
ends of yoke-shaped piece 105 and swing
this member out of engagement with the
piece 101 thereby permitting further down-
ward movement of the lever 100 which,
after raising the stem 41 to the limit is
swung positively downward during the re-
mainder of the downward movement of the
head. Normally the end of the lever 100
stands a short distance below the end of
the stem 41 in order that the head 2 may be
permitted to move downwardly far enough
105 to release the pressure of the lateral dies
upon the heel in the mold before the action
of the lever 100 on the toplift plate begins.
Accurate timing of this operation, however,
is not necessary in the present construction,
since, if the stem 41 engages the lever before
the compressed heel is released, the lever is
merely forced downwardly against the fric-
tion of the rod 102 until the dies are re-
tracted or until the abutment 106 is en-
countered.

While the head 2 is at or near its lower-
most position and while the side dies 22 are
separated to the fullest extent and the plate
40 is in its upper position, the feeding
mechanism, to be hereinafter described, is
actuated to remove a compressed heel from
the plate and deposit a new blank in its place.

Thereupon the upward movement of the head begins. During the first part of this movement the rod 102 will again be held stationary momentarily by friction and the lever 100 immediately swings downward about its fulcrum 112 thus allowing the toplift plate to drop under the influence of gravity. This operation occurs promptly at the beginning of the upward movement of the head so that the uncompressed blank is lowered to the bottom of the mold before the side dies 22 have closed to any appreciable extent. After the lever 100 has been swung away from the stem 41 and the toplift plate has reached its lower position the lever and rod 102 will be drawn upwardly against the friction of the bushing 109 and plunger 104 by the engagement of the shoulder 103' on the forked piece 101 with the top edge of the cam 110 and so returned to normal position.

The reciprocating head 2 has a forward extension 20 which constitutes a table or support for a feeding and ejecting mechanism. This mechanism comprises, among its parts, the slide 60 movable on suitable guides on the table and having pivotally mounted thereon the heel blank engaging arms 61, 61. Grasping plates 62 are pivotally connected with the arms 61 by pins 63 and are adapted to be readily removed and replaced by other plates of different sizes according to the shape and size of the heel blanks to be fed. An abutment 64 is formed on the slide 60 and is adapted to engage the breast of a heel blank. Leaf springs 65 are secured to the arm 61 and arranged to act upon the plates 62 to turn them toward the abutment 64. The spring-pressed plates 62 and the abutment constitute a clamp for embracing and holding a heel or toplift blank while it is being fed into position on the toplift plate 40 beneath the die 25.

The free ends of the arms 61 are provided with enlargements or shoulders 66 to contact with and push a compressed heel off the toplift plate and to the chute 15 when the slide is moved forward to feed an uncompressed heel blank into position on the top lift plate. The adjacent faces of the arms 61 have interlocking segmental gears 59 formed thereon. One of the arms has an extension 67 located between two lugs 68 and 69 on the slide 60. The lug 68 has a socket formed therein and receives a spring-pressed pin 70 which acts to hold the extension 67 normally against the lugs 69 and the arms 61 closed toward each other in position to clamp and hold a heel blank. The lug 69 is provided with a guideway in which there is mounted a beveled sliding block 71 which is arranged to act upon the extension 67 against the action of the spring pin 70 to force the extension 67 of the arm 61 toward

the left in Fig. 5 to separate the arms and 65 release the heel blank.

For actuating the sliding block 71 to separate the arms 61 and deposit a heel blank on the toplift plate there is provided a cam plate 75 rigidly mounted on a bracket 76 fast to the stationary frame of the machine. The cam plate comprises a continuous surface having a substantially vertical portion 77 and an outwardly and downwardly flaring bottom portion 78. The plate is inclined 75 downwardly and rearwardly and is so located with respect to the path of the sliding block 71, as this block is moved upwardly and downwardly with the head 2 and forwardly and rearwardly with the feeding slide 80 60, that the block 71 is forced inwardly to separate the arms 61 when the clamp formed by the plate 62 and the abutment 64 is squarely over the toplift plate 40 and the mold begins to approach the stationary die 25 on the 85 upward movement of the head 2. As already intimated, the operation of depositing the uncompressed blank on the toplift plate is timed to correspond with the beginning of the downward movement of the latter, which 90 occurs with the beginning of the ascending movement of the head. The shape and arrangement of the cam plate are such that whenever the head 2 moves toward the die 25 and the carrier is in its inner position, the 95 arms 61 are separated so that there is no possibility of the arms becoming caught between the mold and the die whether the machine is being turned over in the normal direction or being reversed.

The slide 60 has a tail piece 90 pivotally connected to it and provided on its rear end with a latch bolt 92 to lock it normally in the position shown in Fig. 3. The tail piece 90 is provided on its lower side with ears 105 supporting a roller 93.

94 indicates a bell crank lever pivoted at 95 in the extension 20 of the head 2. The lever 94 is forked at its upper end to engage the roller 93 on the pivoted tail piece, 110 thereby forming a detachable connection between the feeding slide 60 and the lever, which permits the slide to be removed from the machine when the tail piece 90 is unlocked and swung upwardly. The shorter 115 arm of the bell crank lever 94 is connected by a roller 96 with the slotted rod 99 yielding mounted in a sleeve 97 pivoted to a lug formed on the stationary frame of the machine. A spring (not shown) within the 120 sleeve 97 serves to hold the rod 99 normally in an extended position, as shown in Fig. 3.

The slot in the rod 99 forms a lost motion connection between the rod 99 and the lever 94. During the first part of the rise of the 125 reciprocating head 2, the roller 96 travels in the slot and the lever 94 is not actuated to move the feeding slide 60. During the latter

part of the rise of the head 2 the roller comes to the end of the slot and thereafter the lever 94 is actuated to move the slide outwardly. When the head 2 begins to descend the roller 96 again travels the length of the slot without actuating the lever 94 or causing the slide 60 to be moved, giving ample time for the workman to insert a heel blank into the clamp, but after the roller reaches the lower end of the slot the lever 94 is actuated to move the feeding slide 60 inwardly to present the blank to the compressing dies and to eject the compressed heel. The yielding connection between the rod 99 and the sleeve 97 permits yielding of these elements in case the movement of the feeding slide is obstructed or interrupted.

In the form of toplift plate supporting device shown in Figs. 7, 8 and 9, I have entirely dispensed with the filling pieces heretofore used for the purpose of adjusting the vertical position of the said toplift plate with relation to the cross head 2 and have provided means for effecting this adjustment which I shall now proceed to describe.

A recess 115 is formed in the upper portion of the cross head and a wedge shaped block 116 is mounted to slide forwardly and rearwardly in the said recess. Inserted in the under side of said block is an outwardly projecting lug 117 having a downwardly bent forked end. The said forked end engages in an annular groove 118 formed immediately under the head of a screw 119 which is tapped into the cross head 2. The screw 119 is provided with a squared head, as shown, for the purpose of permitting easy adjustment thereof. Superimposed upon the block 116 is a second wedge shaped block 120, the under surface of which corresponds to and engages the upper surface of the block 116.

The block 120, as shown, is shorter than the block 116 and fits between two bars 121 and 122 bridged across the upper portion of the recess 115 so that while the block 116 may have forward and rearward movement in the recess, the block 120 can move only vertically therein. The last-mentioned block 50 is provided with a central hole 123 permitting the passage of the stem 41 of the toplift plate 40. A slot 124 in the lower block 116 permits the passage of said stem through the lower block and allows said lower block 55 to be adjusted horizontally. The stop pin 51 operates to limit the upward movement of the toplift plate in the same manner as previously described. It is essential in machines of this character that the depth of 60 the mold, of which the toplift plate 40 forms the bottom, may be quite accurately determined. This is difficult if wedge blocks having smooth engaging surfaces are employed since the great pressure brought upon

the blocks is likely to produce slipping 65 movement thereof and affect the adjustment. I have therefore provided the engaging surfaces of the blocks 116 and 120 each with a series of steps as shown at 125. As appears clearly from the enlarged section of Fig. 9, each of these steps consists 70 of a flat tread portion and an inclined riser portion 126. In practice, the height of each riser portion is quite small in order to allow a fine adjustment of the height of the top-lift plate. The direction of the tread surfaces of the steps being perpendicular to the line of application of pressure, it will 75 be seen that after adjustment has once been effected, there will be no danger whatever 80 of the parts slipping, no matter how great may be the pressure applied thereto.

An indicating mark 127 is made upon the head of the screw 119 and a corresponding indicating mark 128 is made upon the downwardly projecting portion of the lug 117. The pitch of the screw 119 is such that one rotation, or some aliquot part of a rotation, thereof, will move the block 116 longitudinally a distance equal to the length of one 90 of the steps 125. The indicating marks 127, 128 are so placed that when they register with each other the steps upon the two wedge blocks are in complete engagement 95 as shown in Fig. 9. This is for the purpose of allowing the operator by an inspection 100 of the indicating marks to determine when the adjustment is such that a full bearing surface between the two wedge blocks is obtained in order to support the pressure 105 and to avoid any danger of shearing off the edges of the steps. By reason of the inclination of the risers the stepped formation of the engaging surfaces of the wedge blocks does not interfere with the adjustment 110 thereof by means of the screw. Finger recesses 129 are provided to facilitate the removal of the upper block 120 when desired.

The driving shaft 3 is provided with fast 110 and loose pulleys and with a fly wheel 31.

32 indicates a belt shifter carried on a longitudinally movable rod 35 upon which is also carried a brake 36 in position to engage the fly wheel and stop the machine 115 when the belt is shifted to the loose pulley. The rod 35 is actuated by a rock-shaft 37 having one arm 38 engaged therewith and the other arm 39 provided with a handle within convenient reach of the operator. 120 The rock-shaft 37 may also be provided with a foot treadle by means of which it may be turned to cause the machine to be started.

The operation of the machine is as follows: When the reciprocating head 2 is 125 in its lower position, the several parts of the mechanism occupy the positions shown

in Fig. 1, the heel blank having been fed to the toplift plate and being still held in the grasp of the clamp. When the machine is set in operation by throwing the lever 39, the head 2 begins to rise. Immediately the sliding block 71 encounters the cam plate 75 and is pressed inwardly against the extension 67 separating the arms 61 and opening the clamp which deposits an uncompressed blank upon the toplift plate. The toplift plate which is held in its upper position when the head 2 is in its lower position is allowed to drop to the bottom of the mold carrying with it the blank deposited thereon by the clamp. In the continued rise of the head 2 the arms of the feeding and ejecting mechanism are further separated by the continued action of the cam plate 75 to present a clear space between the mold 20 and the heel seat die 25 and said arms are held in this separated position during the rise of the head 2 and during the subsequent retraction of the feeding and ejecting mechanism. The links 17 for actuating the slides 26 move about their pivots 18 and during the last part of the rise of the head 2 the side compressing dies and breast plate are contracted to close the mold and the heel which is in the mold between the toplift plate and the heel seat die is compressed 30 both laterally and vertically. The feeding and ejecting mechanism is also moved outwardly into position to have a new heel blank put into the heel clamp.

35 On the downward motion of the head 2 the side compressing dies and breast plate are moved to expand the mold and release the compressed heel and thereupon the lever 100 operates to elevate the toplift plate and 40 carry the compressed heel into position to be pushed out to the chute 15. The feeding and ejecting mechanism remains at rest in its outward position during part of the descent of the head 2 and during this 45 period the arms 61 are held separated allowing time for the workman to place an uncompressed blank in the clamp. On the continued downward movement of the head 2 the sliding block 71 moves outwardly on the flaring portion of the cam plate 75 and the clamp is thereupon closed upon the blank by the action of the spring-pressed pin 70. During the latter part of the descent of the head the feeding slide is 50 moved inwardly. When near the end of its movement the shoulders 66 of the arms 61 strike the heel last compressed which is being supported on the elevated toplift plate and push it out into the chute. The inward movement of the slide continues until the clamp is located exactly over the toplift plate in which position the blank is held until released.

55 Having fully described my invention,

what I claim as new and desire to secure 65 by Letters Patent of the United States is:—

1. In a machine of the class described, the combination with compressing dies and a top-lift plate, of mechanism for moving said top-lift plate comprising relatively 70 movable members, a lever pivoted at separate points respectively to each of said members, and frictional means for normally opposing the movement of one of said members. 75

2. In a machine of the class described, the combination with heel compressing dies and a top-lift plate, of mechanism for moving said toplift plate relatively to said dies comprising a pivoted lever and frictional 80 means for actuating said lever.

3. In a machine of the class described, the combination with a reciprocating head, of a mold carried by said head, a top-lift plate movably mounted in said mold, a lever pivoted to said head, and frictional means for turning said lever on its pivot to move said top-lift plate. 85

4. In a machine of the class described, the combination with heel compressing dies 90 and a top-lift plate, of mechanism for moving said top-lift plate relatively to said dies comprising a lever having a movable fulcrum and frictional means normally holding said fulcrum stationary. 95

5. In a machine of the class described, the combination with a die, of a co-operating mold movable toward and from said die, an ejector in said mold and movable relatively thereto, and means comprising a frictionally mounted rod and connections between the rod and the ejector for causing the ejector to rise in the mold during the descent thereof and to drop during the first part of the ascent of said mold. 105

6. In a machine of the class described, the combination with a mold comprising side dies adapted to separate and receive a blank, and then to close and compress said blank, of a movable ejector in said mold 110 normally at the bottom thereof, means for actuating said dies, and means comprising a frictionally mounted rod and connections between the rod and the ejector for raising and lowering said ejector while the dies are 115 separated.

7. In a machine of the class described, the combination with compressing dies and a top-lift plate, of a stationary frame having a friction member mounted therein, a reciprocating head carrying said dies, and mechanism for moving said top-lift plate comprising a lever pivoted at separate points respectively to said frame and said friction member. 120

8. In a machine of the class described, the combination with compressing dies and a top-lift plate, of a frame, a movable

fulcrum-carrying member mounted therein, a reciprocatory head, and mechanism for moving said top-lift plate comprising a lever pivoted at separate points respectively to said frame and said fulcrum-carrying member.

9. In a machine of the class described, the combination with a reciprocatory head, of a mold carried by said head, a top-lift plate, and instrumentalities for causing said top-lift plate to be moved relatively to the mold comprising a frictionally mounted rod, a lever movable with the head, and operatively disposed with respect to said plate, and means for positively preventing movement of said rod beyond a predetermined point without actuating the lever.

10. In a machine of the class described, the combination with heel compressing dies, of a top-lift plate, and mechanism for moving said top-lift plate relatively to said dies comprising a frictionally mounted rod and locking device for said rod.

11. In a machine of the class described, the combination with heel compressing dies, of a top-lift plate, and mechanism for moving said top-lift plate relatively to said dies comprising a rod, frictional means normally opposing movement of said rod, and positive means for preventing movement of said rod beyond a predetermined point.

12. In a machine of the class described, the combination with heel compressing dies, of a movable top-lift plate, positive means for limiting the movement of said plate, and frictional means for moving said plate.

13. In a machine of the class described, the combination with compressing dies and a relatively movable top-lift plate, of mechanism including frictionally connected elements for moving said plate, and a separate device for positively preventing relative movement of said elements.

14. In a machine of the class described, the combination with compressing dies and a relatively movable top-lift plate, of mechanism including frictionally connected elements for moving said plate, and a locking device for rigidly connecting said elements against relative movement in one direction.

15. In a machine of the class described, the combination with compressing dies and a relatively movable top-lift plate, of mechanism including frictionally connected elements for moving said plate, a locking device for preventing relative movement of said elements, and means for rendering said locking device inoperative.

16. In a machine of the class described, the combination with compressing dies and a relatively movable top-lift plate, of mechanism including yieldingly connected elements for moving said plate, a device for preventing relative yielding movement of

said elements after a predetermined relative movement thereof, and means operating at a subsequent point in the cycle of the machine for again permitting relative movement of said elements.

17. In a machine of the class described, the combination with compressing dies and a relatively movable top-lift plate, of mechanism for moving said plate including a lever, frictional means for normally actuating the lever, and positive means arranged to actuate said lever on the failure of said frictional means.

18. In a machine of the class described, the combination with compressing dies and an ejector, of mechanism for moving said ejector comprising a lever having a shiftable fulcrum, means for swinging said lever about its fulcrum to actuate the ejector, and provision for moving said lever bodily after the actuation of the ejector.

19. In a machine of the class described, the combination with a mold of an ejector, and mechanism for actuating said ejector including a pivoted lever, said lever being movable about a center other than its pivot to actuate the ejector, and being further movable bodily without affecting the ejector.

20. In a machine of the class described, the combination with compressing dies and an ejector, of a movable head, an ejector-operating lever pivoted therein, and means for moving said lever about a center other than its pivot to actuate the ejector, and constructed and arranged for allowing movement of the lever without affecting the ejector.

21. In a machine of the class described, the combination with a contractile mold and positive means for contracting it, of means for ejecting a blank from said mold and frictional means for effecting operation of said ejecting means.

22. In a machine of the class described, the combination with a mold, of means for ejecting a blank from said mold, frictional means for effecting operation of said ejecting means, and means for positively operating said ejecting means upon failure of said frictional means.

23. A machine of the class described, having, in combination, a driving shaft, a mold comprising blank compressing members movable toward and from each other; separate means, comprising movable grippers, for feeding a blank to said mold; and means regardless of the direction of rotation of the driving shaft for positively insuring the opening of the grippers whenever the blank compressing members approach each other.

24. A machine of the class described having, in combination, a driving shaft, a stationary die; a movable mold, separate means, comprising movable grippers, for feeding a

blank to said mold; and means regardless of the direction of rotation of the driving shaft for positively insuring the opening of the grippers whenever the blank compressing members approach each other.

25. A machine for operating upon parts of boots or shoes, comprising the combination, with a compressing mold comprising stationary and movable dies, of feeding mechanism, including pivoted blank engaging arms, movable with the movable die toward and from the stationary die, and a plate mounted in fixed relation to the stationary die and having a downwardly inclined cam face constructed and arranged to separate the said pivoted arms, in any position which they may assume, whenever they approach the stationary die and hold them separated until they recede from the stationary die.

26. In a machine of the class described, the combination with a compressing mold and a top-lift plate, of mechanism for moving said top-lift plate relatively to said mold including a lever and an acuating device therefor frictionally mounted on a stationary part of the machine.

27. A heel compressor having a compressing mold provided with a bottom which is adjustable to vary the depth of the mold, and means for effecting the adjustment, comprising coöperating wedges the engaging surfaces of which are correspondingly stepped.

35. 28. A heel compressor, having, in combination, a stationary follower, a supporting member mounted for reciprocation toward and from said follower, a mold mounted upon said supporting member, said mold being provided with a bottom which is movable therein, a vertically movable wedge block upon which the bottom of said mold is supported and a horizontally movable wedge block engaging said vertically movable wedge block whereby the depth of said mold may be adjusted.

29. In a machine of the class described, the combination of a mold having a movable bottom plate, a depending post attached to said bottom plate, a vertically movable wedge block upon which said bottom plate is supported, said wedge block having an aperture through which said post extends and a second wedge block movable with relation to said first mentioned wedge block and having a slot through which said post passes.

30. A machine for compressing boot or shoe parts having, in combination, a compressing member and means for adjustably supporting said compressing member, said means comprising coöperating wedges, the engaging surfaces of which are stepped.

31. A machine for compressing boot or

shoe parts comprising the combination with 65 a stationary compressing member, of a movable compressing member, a movable support upon which said last named member is mounted, and means, comprising wedges having stepped engaging surfaces, for adjusting said movable compressing member with relation to its support.

32. A machine for compressing boot or shoe parts, having a compressing member and means for adjustably supporting said 75 compressing member, said means comprising coöperating wedges, the engaging surfaces of which are stepped, the riser portions of the steps being inclined with relation to the tread surfaces thereof.

33. A machine for compressing boot or shoe parts, having, in combination, a stationary follower, a reciprocatory head, side dies, mounted upon said head and constituting a mold, a top-lift plate mounted within 85 said mold and forming the bottom thereof, coöperating wedge blocks upon which said top-lift plate is supported, the engaging surfaces of said wedge blocks being stepped, and means for adjusting one of said wedge 90 blocks with relation to the other.

34. A machine for compressing boot or shoe parts, having, in combination, compressing members relatively movable toward and from each other, mechanism, comprising stepped wedges, one of which is movable with relation to the other, for adjusting one of said compressing members, and means for indicating when the steps of one of said wedges are in full engagement 100 with those of the other.

35. A machine for compressing boot or shoe parts having, in combination, compressing members relatively movable toward and from each other, a vertically movable wedge block upon which one of the compressing members is sustained, a horizontally movable wedge block coöperating with said vertically movable wedge block, the engaging surfaces of said blocks being 110 formed in steps, means for adjusting said horizontally movable wedge block and means for indicating when the steps of one block are in full engagement with those of the other.

36. A machine of the class described, having, in combination, compressing members, relatively movable toward and from each other, a vertically movable wedge block upon which one of the compressing members 120 is sustained, a horizontally movable wedge block coöperating with said vertically movable wedge block, the engaging surfaces of said blocks being formed in steps, a screw for adjusting said horizontally movable 125 wedge block, the pitch of said screw having such relation to the length of each of said steps that one revolution of the screw will

advance its wedge the distance of a step, and means for indicating the revolutions of the screw.

37. A machine for compressing boot or shoe parts comprising an adjusting device having, in combination, a stepped wedge adjusting member, a coöperating member having a stepped surface for engagement with said wedge member, and means whereby said wedge member may be moved in a direction to increase the effective thickness of the adjusting device.

38. A machine for compressing boot or shoe parts comprising an adjusting device having a stepped wedge member, a stepped member engaging said wedge member, and means for relatively adjusting said members in the direction of succession of the steps.

39. A machine for compressing boot or shoe parts comprising the combination of a stepped adjusting wedge member, a coöperating member having a stepped surface for engagement with said wedge member, and means whereby said wedge member may be moved in a direction from the thick edge toward the thin edge thereof.

40. In a machine of the class described, the combination with a movable mold, of means for ejecting a blank from the mold and frictional means, brought into action by movement of the mold, for effecting operation of the ejecting means.

41. A machine for operating on parts of boots or shoes comprising the combination with a compressing mold and movable feeding mechanism, including relatively movable blank engaging arms, of stationary means for separating the arms and keeping them separated in any position which they may assume, during each compressing operation of the machine.

42. In a machine of the class described,

the combination with a contractile compressing mold and feeding mechanism, including pivoted blank engaging arms, of a stationary cam constructed and arranged to separate the arms and keep them separated, in any position which they may assume, whenever the mold is contracted.

43. In a machine of the class described, the combination of a compressing mold comprising parts relatively movable toward and from each other, mechanism for ejecting a blank from the mold when the parts are separated, said mechanism including relatively movable members in frictional engagement with each other, and means for returning said members to initial relation after relative movement thereof.

44. In a machine of the class described, the combination of a compressing mold, means for ejecting a blank from the mold, frictional means, comprising relatively movable elements, for operating said ejecting means, and means for restoring said elements to initial relation after relative movement thereof.

45. In a machine of the class described, the combination of a compressing mold, a movable member for ejecting a blank from the mold, frictionally operated mechanism, comprising relatively movable parts, for operating the ejecting member, and positive means for restoring said frictionally operated mechanism after relative movement of its parts.

In testimony whereof I have signed my name to this specification in the presence of two subscribing witnesses.

THOMAS LUND.

JOSEPH B. GILBERT.

Copies of this patent may be obtained for five cents each, by addressing the "Commissioner of Patents, Washington, D. C."

It is hereby certified that in Letters Patent No. 1,172,471, granted February 22, 1916, upon the application of Thomas Lund, of Beverly, Massachusetts, for an improvement in "Compressing-Machines," errors appear in the printed specification requiring correction as follows: Page 7, lines 120-122, claim 23, and page 8, lines 1-2, claim 24, strike out the words "regardless of the direction of rotation of the driving shaft"; page 7, line 124, and page 8, line 5, before the periods, claims 23 and 24, insert the words *regardless of the direction of rotation of the driving shaft*; and that the said Letters Patent should be read with these corrections therein that the same may conform to the record of the case in the Patent Office.

Signed and sealed this 2d day of May, A. D., 1916.

[SEAL.]

R. F. WHITEHEAD,

Acting Commissioner of Patents.
